CLAIM

The ornamental design for a camera, as shown and described.

DESCRIPTION

FIG. 1 is a front view of a camera;

FIG. 2 is a rear view of the camera;

FIG. 3 is a left view of the camera;

FIG. 4 is a right view of the camera;

FIG. 5 is a top view of the camera; and,

FIG. 6 is a bottom view of the camera.

The broken lines in the drawings illustrate portions of the camera that form no part of the claimed design.
